UNITED STATES PATENT OFFICE.

WILLIAM W. KIDENEY, OF CHICAGO, ILLINOIS, ASSIGNOR TO AMERICAN ELECTRIC COMPANY, OF CHICAGO, ILLINOIS, A CORPORATION OF ILLINOIS.

PHONOGRAPH.

1,279,357.

Specification of Letters Patent. Patented Sept. 17, 1918.

Application filed October 9, 1916. Serial No. 124,463.

To all whom it may concern:

Be it known that I, WILLIAM W. KIDENEY, a citizen of the United States of America, and resident of Chicago, Cook county, Illinois, have invented a certain new and useful Improvement in Phonographs, of which the following is a specification.

My invention relates to an improvement in phonographs, and has for its object means for automatically causing the needle or stylus carried by the sound box to automatically engage the sound record when the machine is started in operation and to likewise automatically separate these elements when the machine is stopped.

In prior constructions in which the needle has been manually brought into engagement with the sound record there is danger that the record will be scratched or otherwise injured owing to improper engagement between the needle and the record. For example in such constructions the needle may be accidentally moved laterally across the record thus materially injuring the same. By my invention, however, I overcome such defects as the needle is brought automatically into proper engagement with the record and thus all danger of scratching or other injury to the record is eliminated.

In the accompanying drawing I have illustrated one embodiment of my invention in which the table carrying a disk record is automatically raised into a position adjacent to the needle or stylus when the machine is started in operation. I have not illustrated all the details of the phonograph mechanism such as the amplifying horn or box or other auxiliary features as these can be of any well-known construction and form no part of my present invention. In these drawings I have illustrated merely one form of mechanism for carrying out the features of my invention.

Figure 1 is a transverse sectional view of a machine embodying the features of my invention;

Fig. 2 is a sectional view taken on the line 2—2 of Fig. 1;

Fig. 3 is a sectional view taken on the line 3—3 of Fig. 2;

Fig. 4 is a detail view of a modified form of weight; and

Fig. 5 is a detailed view on line 5—5 of Fig. 2.

As illustrated, I have shown a suitable

inclosing casing 5, to the cover of which a supporting member 6 is secured. This supporting member is provided with suitable depending brackets for supporting the various parts of the operating mechanism. 60 Thus a bracket 7 is provided for supporting a suitable motor 8. I have shown this motor in the form of an electric motor although it will be obvious that other forms of motive power can be employed such as the well known type of spring motor, but for convenience I have illustrated my invention in connection with an electric motor. Power is transmitted from this motor to the transmitting shaft 9 which is provided with a 70 worm 10 which meshes with the worm gear 11. This worm gear is mounted on a sleeve 12 in which the operating spindle 13 is slidably mounted—that is these two members are keyed together in such a manner 75 that the spindle 13 is free to move longitudinally with respect to the sleeve 12, but no relative rotative movement between these two members is permitted. This spindle passes through an opening in the cover of 80 the inclosing casing and carries on its upper end the revolving table 14 of the usual well known construction, which table supports the disk record. A suitable needle or stylus 39 carried by the sound box 39^a is provided, 85 these elements being of any well known or desired construction. This stylus is so mounted with respect to the record that it is adapted to engage the record only when the table is in raised position as will be herein- 90 after more fully described.

Mounted on the opposite or lower end of the spindle is a suitable block 15 which contains a socket 16 within which the lower end of the spindle revolves. Secured to this 95 block 15 is a yoke member consisting of the arms 17, 18 which are pivotally mounted on the pin 19 mounted in the depending bracket 20. At their opposite ends these two arms are brought together and a counter 100 weight 21 is pivotally mounted on the same. The movement of this weight is limited, however, by a stop 22, the purpose of which movement will be hereinafter more clearly pointed out. This weight is sufficient to 105 substantially counter-balance the weight of the table 14 and in order to obtain a proper balance the position of this weight is rendered adjustable along the arms 17 and 18 by reason of the slot 23 clearly shown 110

in Fig. 3. This weight is normally slightly over-balanced—that is it has a tendency to rock forward so that the stop 22 engages the arms 17 and 18. It is normally maintained in its upward position by means of a connection consisting of a spring 24 suitably secured to the weight by means of the eye 25, the opposite end of this spring being secured to the lever 26 pivotally mounted on the pin 27 carried by a depending portion of the member 6. The opposite end of this lever 26 is bent upwardly and is curved so as to present a flat end portion 28 which is opposite a pin 29. This pin 16 is carried by a sleeve 30 which is slidably mounted on the shaft 9. A suitable speed governor is provided, this governor consisting of a plurality of spring arms 31 carrying the weights 32, one end of these 20 arms being secured to the sleeve 33, secured to the driving shaft 9, while the other end of these arms are secured to the sliding sleeve 30. A friction disk 34 is likewise carried by the sliding sleeve 30 being adapted 25 to be brought into engagement with the friction members 35 carried by the yoke member 36. This yoke member extends upwardly, as shown in Fig. 3, and is then bent into a horizontal position and is pivotally 30 mounted on the pin 37 carried by the supporting member 6. The movement of this yoke is controlled by means of a suitable controlling lever 38 whereby the yoke members may be rocked so as to move the friction members 35 toward or from the disk 34 whereby the speed may be regulated in a manner which will be hereinafter more clearly understood.

With this construction it will be noticed 40 that normally the end 28 of the lever 26 is in engagement with the end of the pin 29 and thus the lower end of this lever is prevented from moving to the left, as shown in Fig. 2. And in this manner the weight

45 21 is held in its upper position as shown in full lines in Fig. 3. When the weight is in this position the weight of the table slightly over balances the counter-weight and thus the table remains in its lower position.

50 When, however, the machine is started in operation, by closing the circuit of the electric motor for example, the driving shaft 9 is rotated and transmits its movement to the revolving table 14 through the worm 55 and gear connection previously described.

At the same time this rotation of the shaft 9 causes the weights 32 of the speed governor to fly outwardly and thus draw the sleeve 30 along the shaft 9 and withdraw 60 the pin 29 from engagement with the flat end portion 28 of the lever 26. This lever is then free to rock slightly and owing to the overbalanced position of the weight 21 this weight rocks forward until the stop 22 65 strikes the arms 17 and 18. In this position

of the weight the revolving table is slightly overbalanced and thus the arms 17 and 18 are rocked so as to cause the weight to move downward and the ends secured to the block 15 in which the lower end of the spindle 70 30 is mounted to move upwardly into the position shown in dotted lines in Fig. 3. This upward movement of the spindle 13 causes the revolving table and record to move upwardly into the position shown in 75 dotted lines in Figs. 1 and 3 in which position the record is brought into proper operative relation with the needle or stylus 39. The table is maintained in this position during the operation of the machine but as soon as the motor is stopped the weights 32 are no longer actuated by centrifugal force and the spring tension of the arms 31 operates to draw these arms and weights inward back to their normal position and thus slide the sleeve 34 and the pin 29 along the shaft to the right, as shown in Fig. 2. The end of the pin 29 thus presses against the flat end portion of the pivot lever 26 and in this manner rocks this lever so as to produce an upward pull on the weight 21 through the spring connection 24. This pull tends to tilt the weight 21 backward with respect to the arms 17, 18 in which position the table and disk overbalance the weight. This shifting of the position of the weight 21 together with the pull exerted on the weight through the lever 26 and spring 21, due to the pressure on the end 28 exerted by the pin 29, is sufficient to cause the arms 17 and 18 to rock back into their normal position—that is permit the revolving table and record to move downwardly into the normal position out of engagement with the stylus or needle. In this manner the needle or stylus is automatically disengaged from the record when the machine stops.

In Fig. 4 I have shown a modified form for the counter weight. As there shown the weight 21^a instead of being pivotally mounted on the arms 17, 18, is slidably mounted on these arms. With this construction the weight is adjusted on the arms so as to slightly overbalance the weight of the table. 110 The weight is normally held in its upper position by means of the connection through the pivoted lever 26, as in the preferred form of my invention, and when the machine starts in operation, thus permitting this lever 115 to tilt about its pivot, the weight then operates to move the table into its raised or upper position. When the machine stops the pull exerted through the connection to the pivoted lever 26 operates to draw the weight back 120 into its upper position and thus again lowers the table so as to disengage the stylus from the record.

In order to vary the speed of the device the speed adjusting levers 38 are operated 130

so as to vary the position of the friction knobs 35 and thus vary the friction between these knobs and friction disk 34. In this manner the speed of the operating shaft can 5 be readily adjusted, although other suitable speed adjusting mechanism can be employed without departing from the spirit of my invention.

It will thus be seen that I have devised a 10 very efficient mechanism for automatically bringing the sound record into operative relation with the stylus. It will be noticed that this mechanism is entirely independent of the driving mechanism—that is no extra 15 load is placed upon the driving mechanism by reason of the fact that the table is raised and lowered into operative position. This feature is of importance as it enables a smaller sized motor to be employed than 20 would be the case where the motive power itself was directly employed to raise and lower the table.

While I have illustrated and described one embodiment of my invention and one in 25 which the revolving table is moved relative to the stylus it is obvious that the stylus could be automatically moved instead of the table without departing from the broader aspects of my invention. Various other 30 changes and modifications can be made without departing from the spirit of my invention.

What I claim as my invention is:

1. In a phonograph, a stylus, a revolving- 35 member carrying a sound-record, said stylus being normally out of engagement with said record, driving means for said revolving-member, and means including an element adapted to operate independent of said driving 40 means for automatically causing said stylus to engage with said record when said member is started into operation.

2. In a phonograph, a stylus, a revolving-member carrying a sound-record, said stylus 45 being normally out of engagement with said record, driving means for said revolving-member, and means including an element adapted to operate independent of said driving 50 means for automatically causing said stylus to engage with said record when said member is started into operation and for separating said stylus and record when said revolving member ceases its operation.

3. In a phonograph, a stylus, a revolving 55 table carrying a disk record, said stylus being normally out of engagement with said record, driving means for said table, and means including an element adapted to operate independent of said driving means 60 for causing said stylus to engage said record when said table is started into operation, and for automatically separating said stylus and record when said revolving table is stopped.

4. In a phonograph, a stylus, a revolving 65 member, a sound-record carried thereby, said

stylus being normally out of engagement with said record, means for counter-balancing the weight of said revolving member and record, and means for automatically moving said record into engagement with said stylus 70 when said revolving member is started into operation.

5. In a phonograph, a stylus, a revolving member, a sound-record carried thereby, said stylus being normally out of engagement 75 with said record, means for counter-balancing the weight of said revolving member and record, and means for automatically moving said record into engagement with said stylus when said revolving member is started into 80 operation, and for disengaging said record and stylus when said revolving member is stopped.

6. In a phonograph, a stylus, a revolving table for carrying a disk record, said stylus 85 being normally out of engagement with said record, driving means for said table, automatic means controlled by said driving means for raising and lowering said revolving table upon said machine being started 90 and stopped, respectively, said automatic means including means for counter-balancing the weight of said revolving table.

7. In a phonograph, a stylus, a revolving table carrying a sound-record, said stylus 95 being normally out of engagement with said record, means for rotating said table, a governor for controlling the speed of rotation of said table, and means controlled by said governor for automatically raising said table 100 into a position whereby said stylus engages the sound-record.

8. In a phonograph, a stylus, a revolving table carrying a sound-record, normally located in a plane below that of the stylus, 105 means for counter-balancing the weight of said revolving table, driving means for said table, a governor for regulating the speed of said driving means, and means controlled by said governor for causing said table to be 110 raised so that said record is brought into the plane of said stylus.

9. In a phonograph, a stylus, a revolving table carrying a sound-record normally disengaged from said stylus, a counter-weight 115 for said table and record whereby said table and counter-weight are substantially in a state of equilibrium, driving means for said table, a centrifugal governor driven by said driving means, and means controlled by said governor for causing said table to be raised and lowered, whereby said stylus is brought into and out of engagement with said record.

10. In a phonograph, a pivoted lever, a revolving table mounted on one end of said 125 lever and a counter-weight pivotally mounted on the opposite end of said lever, said weight being normally held in position whereby said table overbalances said weight, and means for permitting said 130

weight to tilt forward so that said weight overbalances said table.

11. In a phonograph, a pivoted lever, a revolving table supported by one end of said lever, a counter-weight on the opposite end of said lever for balancing the weight of said table, driving means for said table and means controlled by said driving means and including said counter-weight for causing said lever to be tilted so as to raise said table upon said machine being started into operation.

12. In a phonograph, a pivoted lever, a revolving member supported by one end of said lever, a tilting weight on the other end of said lever, a stop for limiting the movement of said weight, means for normally holding said weight in its upper position, in which position said table overbalances said weight, and means controlled by the operation of said revolving member for permitting said weight to tilt forward in which position the weight overbalances said table.

13. In a phonograph, a pivoted lever, a revolving table mounted on one end of said lever, a counter-weight mounted on the opposite end of the lever, driving means for said member, a speed governor operated by said driving means, and means controlled by said governor and said weight for automatically raising and lowering said revolving table.

14. In a phonograph, a pivoted lever, a revolving table mounted on one end of said lever, a counter-weight mounted on the opposite end thereof, driving means for said table, a speed governor, a sliding pin controlled thereby, a pivoted arm, a connection from one end of said arm to the said weight, the other end of said arm normally engaging said pin so as to prevent movement of said lever to thereby prevent movement of said weight, and means controlled by the operation of said governor for moving said

pin from said arm to thereby permit movement of the same whereby said weight is free to move to cause said pivoted member to be rocked so as to raise said table.

15. In a phonograph, two arms pivotally mounted, said arms at one end being separated and having secured therebetween a bearing block, a spindle revolvably mounted in said block, a table carried by said spindle, and a counter weight mounted on the opposite end of said arms.

16. In a phonograph, two arms pivotally mounted, said arms at one end being separated and having secured therebetween a bearing block, a spindle revolvably mounted in said block, a table carried by said spindle, a sleeve keyed to said spindle so as to permit a sliding movement of said spindle with respect to said sleeve, and means for rotating said sleeve and spindle.

17. In a phonograph, a spindle, a revolving table carried by said spindle, a sleeve secured to said spindle, means for rotating said sleeve and spindle, and means for sliding said spindle longitudinally with respect to said sleeve.

18. In a phonograph, a stylus, a revolving table carrying a disk record, said stylus being normally out of engagement with said record, means for automatically raising and lowering said table, and means for retarding the downward movement of the same.

19. In a phonograph, a revolving table adapted to be raised and lowered, operating mechanism and a lifting member connected to said operating mechanism for automatically raising said table when the machine is started in operation.

Signed by me at Chicago, Illinois, this 16th day of September, 1916.

WILLIAM W. KIDNEY.
